INSOLE ASSEMBLING MACHINE

George F. C. Burke, Beverly, Mass., assignor to
 United Shoe Machinery Corporation, Flemington, N. J., a corporation of New Jersey

Application February 23, 1952, Serial No. 273,023

12 Claims. (Cl. 12—17)

1

This invention relates to machines for making insoles and is herein illustrated as embodied in mechanism for assembling insole blanks and ribbed canvas material.

In United States Letters Patent No. 2,538,776 granted January 23, 1951, in the name of Stanley M. Griswold, there is disclosed a method of making paired insoles for welt work. In carrying out the method, use is made of an insole-shaped matrix having a groove in each of its opposite faces corresponding in outline to the rib of one of a pair of insoles. The matrix is covered on each side with an all over layer of canvas or Gem duck cemented on its outer face and the canvas is tucked into the grooves to form ribs after which insole blanks or body layers similarly coated are located upon each side of the matrix with the cemented sides toward the cemented side of the canvas layers and the whole assembly is subjected to pressure to cause the insole blanks to become firmly bonded to the canvas.

It is an object of the present invention to provide mechanism for quickly gaging or spotting insole blanks in accurate relation to the canvas layers positioned upon opposite faces of a matrix.

To this end, and as illustrated, the mechanism comprises a support for a matrix and two leaves pivotally mounted upon opposite sides of the support and having means for supporting insole blanks, together with power operated means for closing the leaves. Preferably, and as shown, the leaves have blank retaining means which are retractable upon movement of the leaves toward the matrix thereby to permit close approach of the blanks to the matrix. Preferably, too, the matrix support is movable in a direction heightwise of the leaves in order to engage a tripping device for initiating an operation of power operated mechanism for closing the leaves.

These and other features of the invention are disclosed in the following specification and in the accompanying drawings and are pointed out in the claims.

In the drawings,

Fig. 1 is a perspective view of the upper portion of an insole pressing machine provided with insole spotting or gaging mechanism constructed in accordance with the invention;

Fig. 2 is a perspective view of a matrix with two insole blanks positioned thereon;

Fig. 3 is a side view, partly in section, of the spotting mechanism shown in Fig. 1;

Fig. 4 is a view in front elevation of the spotting mechanism;

2

Fig. 5 is a cross sectional view taken along line V—V of Fig. 3;

Fig. 6 is a cross sectional plan view taken along line VI—VI of Fig. 3; and

Fig. 7 is a cross sectional view taken along line VII—VII of Fig. 3.

The mechanism herein illustrated is adapted to carrying out in part the method of making insoles disclosed in the aforementioned Griswold Letters Patent. To that end, means hereinafter described are provided for locating two insole blanks or body portions 10, Fig. 1, in alignment with a matrix 12, opposite faces of which are covered with pieces of canvas 14, contiguous surfaces of the canvas and blanks having been precoated with adhesive, and thereafter applying pressure to the matrix and blanks to secure the body portions 10 and canvas pieces 14 together in assembled relation as shown in Fig. 2.

The spotting mechanism is mounted upon a bracket 16 extending from the upper portion of the frame 18 of an insole pressing machine generally indicated by reference character 20. The mechanism comprises supports 22 and 24, Figs. 3 and 4, for the edge faces of the matrix, said supports being carried by the bracket 16 and two leaves 26 pivotally mounted on the bracket upon opposite sides of the matrix for angular movement relatively thereto.

The matrix supports are in the form of plates extending in a vertical plane and have upon their upper edges, ribs 28 constructed and arranged to enter a circumferential groove 30 in a matrix when the latter is positioned upon the supports.

Means are provided for adjusting the supports 22 and 24 heightwise of the bracket 16. To that end the support 22 has a depending portion 32, Figs. 3 and 5, slidably mounted in gibs 34 secured by screws 35 to the bracket 16. The lower end of the portion 32 has a lateral flange 36 receiving an adjusting screw 38 rotatably mounted in a plate 40 secured to the gibs by screws 42. Adjustment of the support heightwise of the bracket 16 is obtained upon rotation of the screw 38. A spring 44, Fig. 4, between a knurled nut 46 on the screw and the plate 40 acts to retain the support in adjusted position.

The means for adjusting the position of the support 24 comprises a slide 48, Fig. 6, mounted in gibs 50. The slide 48 is arranged slidably to receive a depending portion 52 of the support 24, adjustment of the support being accomplished by a screw 54 having a knurled head 55, Fig. 3, and rotatably mounted, against pressure of a spring 57, in a plate 56 secured to the slide by

screws 58. The slide 48 is yieldingly retained in its uppermost position by a spring 60 extending from a pin 62 on the lower portion of the slide to a pin 64 on one of the gibs 50. This construction while providing adjustment of the matrix support 24 also provides for a slight downward movement of the support and slide 48 to initiate operation of the leaves 26 as will be hereinafter described.

It is to be noted that the bracket 16 is tilted forwardly and downwardly at an angle of about 30° to the horizontal, Fig. 3, thus to present the matrix supports 22 and 24 and the leaves 26 in a convenient position for insertion of the work. A matrix, when located upon the supports, will be located laterally by the ribs 28. It is held in a predetermined position along the supports by the action of gravity forcing it against a stop 66 having a shank 68 which is slidably mounted in a bracket 70, Fig. 4, secured by screws 72 to an upwardly extending portion 74 of the bracket 16. The bracket 70 carries ways 76 engaging the shank 68, and there is a stop adjusting screw 78 having a knurled head 79 and rotatably mounted, against pressure of a spring 81, in a plate 80 which is secured to the bracket 70 by screws 82.

The leaves 26 are in the form of elongated plates, the lower portions of the ends of which are provided with bosses 84 and 86 through which pass pins 88 and 90, Fig. 3, pivotally to mount the leaves upon brackets 92 and 94 on the main bracket 16. The pivotal mountings for the leaves are so spaced that when the leaves are in vertical position the distance between them is somewhat greater than the thickness of the assembled matrix and insole blanks. Means are provided for supporting insole blanks heightwise of the leaves 26. Such means comprise an abutment 96, Fig. 7, extending longitudinally of each leaf and secured thereto by screws 98.

In order to facilitate positioning insole blanks upon the abutments and for retaining the blanks on the leaves during initial movement thereof toward the matrix each leaf is provided with two retaining members 100 located near opposite ends of the leaf. Each member is in the form of a U-shaped plate, one leg 102 of which is slidably mounted in gibs 104 secured to the outer face of the leaf by screws 106. The plate extends through an opening 108 in the leaf and has an upstanding leg 110 of sufficient length normally to extend above the upper face of the abutment 96 when the leaves 26 are in open position as shown in full lines in Fig. 4. In this position the leg 110 acts as a guide for positioning and retaining a blank on the abutment.

To effect withdrawal of the retaining members 100 when the leaves approach the matrix the plate 102 is caused to be moved downwardly by means of a link 112 having one end pivotally mounted upon the plate at 114 and having its other end pivoted at 116 to a bracket 118 secured to the bracket 16.

For locating insole blanks lengthwise of the leaves 26 there are provided abutments 120, Fig. 4, secured by screws 122 to the inner faces of the leaves. These abutments extend substantially at right angles to abutment 96 and are arranged to engage the heel end portion of an insole blank.

The means for applying pressure to the blanks upon closing the leaves with the matrix and blanks in alinement comprises stiff leaf springs 124 positioned in grooves 126 in the upper por-

tions of the inner faces of the leaves 26, the springs being secured at their outer ends to the leaves by rivets 128. This construction is such that when the leaves are closed the springs 124 exert pressure over a limited area only of the insole blanks in effecting a bonding of the blanks to the matrix sufficient temporarily to secure the blanks in position with their edge portion in predetermined approximate alinement with the edges of the matrix. The upper edges of the leaves near the central portions thereof, forwardly of the springs 124, are curved inwardly at 129, Fig. 3, to provide clearance for the fingers of the operator in placing the insole blanks upon the leaves and to facilitate removal of the matrix after the blanks have been applied thereto.

The leaves 26 are closed by means of a solenoid 130, Fig. 3, having an armature 132 connected by a link 134 to one arm 136 of a bell crank lever 138 pivoted at 139 to the plate 16. The other arm 140 of the lever carries a horizontally extending pivot rod 142 having ears 144 at the ends thereof. Extending upwardly through the ears are bolts 146 screw threaded to links 148 which are pivoted at 150 to bifurcated brackets 152 secured by rivets 154 to the lower central portions of the outer faces of the leaves 26. Springs 156 surrounding the rods 146 between the links 148 and the ears 144 are operative to force the leaves 26 toward each other under yielding pressure when the solenoid is actuated.

Initiation of operation of the solenoid is accomplished by means of a stud 162, Fig. 3, on the sliding member 50, the stud being arranged when the member is depressed to engage a screw 164 on a lever 166 pivoted at 168 on the bracket 16. Angular movement of the lever effects engagement with a button 170 of a switch 172 for energizing the solenoid 130.

The spotting mechanism above described is shown as mounted upon the insole pressing machine 20, Fig. 1, which is provided with two pairs of pressure rolls, generally indicated by reference character 174, through which a matrix with insole blanks spotted thereon can be passed in order permanently to bond together the blanks and canvas.

It is to be understood that the matrix supports 22, 24 and the leaves 26 are constructed and arranged to facilitate the spotting of insole blanks relatively to matrices of various sizes and shapes. To this end, the abutments 96 and 120 on the two leaves are so arranged that when the leaves are closed in the positions indicated by the dot-dash lines of Fig. 4, corresponding abutments are in alinement. As a result, the insole blanks are supported by the leaves with their edges in horizontal alinement and lying in parallel vertical planes which are also parallel to the faces of the matrix.

Prior to assembling a run of insoles of the same size, a typical matrix to which reinforcing material has not been applied is placed upon the supports 22 and 24. The heel stop 66 is adjusted longitudinally of the frame member 16 by means of the screw 18, and the supports 22 and 24 are adjusted heightwise of the member by screws 38 and 58. These adjustments can be made with the leaves 26 closed and with an uncoated insole blank on one of them, the position of the matrix being shifted until it is centered relatively to the edges of the blank. In this connection it is to be noted that the blanks used with a particular matrix are sufficiently larger than the matrix, so that their

marginal portions will extend beyond the matrix by $\frac{1}{4}$ to $\frac{3}{8}$ inch. This provides allowance for trimming the assembled insoles to the contour of the matrix.

In operating the mechanism a pair of insole blanks are placed upon the leaves 26, Fig. 1, with the adhesively coated faces facing each other. Each blank is positioned with an edge resting on one of the abutments 96 and with forepart and heel part edge portions located behind the retaining members 100, the heel end portions being positioned against an abutment 120. A matrix 12 having canvas located upon its opposite faces is positioned on the supports 22 and 24 with the ribs 28 of the support extending into the groove 30 of the matrix, and with the heel end of the matrix in contact with the stop 66. The operator then exerts downward pressure upon the forepart of the matrix resulting in downward movement of the slide 48 which, through stud 162 and lever 166, actuates the switch button 170 causing an operation of the solenoid 130. The solenoid rotates the lever 138 in a clockwise direction applying pressure through the springs 156 to the leaves causing them to close. When the leaves approach the matrix the retaining members 110, through the action of links 112, are retracted permitting engagement of the insole blanks with the canvas. As the leaves are forced toward the matrix the leaf springs 124 press the foreparts of the blanks against the canvas with sufficient force to effect bonds over portions of the abutting adhesively coated surfaces.

The operator holds the forepart of the matrix depressed until the leaves have closed, then removes the matrix and the assembled insoles from the machine. As the forepart of the matrix is raised by sliding it upwardly past the springs 124, the spring 60 forces the support 24 upwardly effecting a release of the switch button 170 and causing the current through the solenoid to be shut off with the result that the leaves are returned to their open positions under the action of the force of gravity which forces the lever 138 and its associated parts in a counterclockwise direction, Fig. 3.

Subsequent to the removal of the matrix it is passed through the rolls 174 which complete the bonding of the insole blanks with the reinforcing material.

Having thus described my invention what I claim as new and desire to secure by Letters Patent of the United States is:

1. An insole spotting machine comprising a frame, a matrix support carried by the frame, leaves pivotally mounted upon opposite sides of the matrix support, insole blank supporting and locating means carried by the leaves, and power means for angularly moving the leaves and blanks supported thereon toward the matrix.

2. An insole blank spotting machine comprising means for supporting a matrix in vertical position, leaves pivotally mounted upon opposite sides of the supporting means, insole blank supporting means, insole blank supporting means on the leaves, power means for closing the leaves, and means responsive to pressure applied to the matrix supporting means for initiating operation of the power means.

3. An insole blank spotting machine comprising means for supporting a matrix in a vertical plane, leaves pivotally mounted upon opposite sides of the matrix supporting means, insole blank supporting means on the leaves,

means for varying the position of the matrix heightwise and longitudinally of the blank supporting means, power means for moving the leaves toward a matrix located on the matrix supporting means, and means responsive to pressure applied to the matrix supporting means for initiating operation of the power means.

4. In a machine of the character described, a frame member, a support for a matrix carried by the frame member, a plurality of leaves pivotally mounted on the frame member upon opposite sides of the support for angular movement toward and away from the matrix, each of the leaves having insole blank supporting means, means for adjusting the position of the matrix heightwise of the support and longitudinally of the frame member, power operated means for closing the leaves, and means operable in response to depression of the matrix support for initiating operation of the power means.

5. An insole spotting machine comprising a frame, a matrix support carried by the frame, leaves pivotally mounted upon opposite sides of the support, power means for moving the leaves angularly toward a matrix positioned upon the support, each of the leaves having an abutment for supporting an insole blank, and resilient means carried by the leaves for pressing the blanks against the matrix, and means responsive to the pressure applied to the matrix to initiate an operation of the power means.

6. An insole spotting machine comprising a frame, a matrix support carried by the frame, leaves pivotally mounted upon opposite sides of the support, insole blank supporting and positioning means carried by the leaves, means for moving the leaves and insole blanks supported thereon toward a matrix positioned upon the support, and resilient means carried by the leaves for pressing the insole blanks against the matrix.

7. An insole spotting machine comprising a frame, a matrix support carried by the frame, leaves pivotally mounted upon opposite sides of the support, means for moving the leaves angularly toward a matrix positioned upon the support, means for positioning the matrix heightwise and longitudinally of the frame, and means on each of the leaves for supporting an insole blank.

8. An insole spotting machine comprising a frame, a matrix support carried by the frame, leaves pivotally mounted upon opposite sides of the support, power means for moving the leaves angularly toward a matrix positioned upon the support, abutments on the leaves for supporting insole blanks, and resilient means carried by the leaves for pressing the blanks against the matrix.

9. An insole spotting machine comprising a frame, a matrix support carried by the frame, leaves pivotally mounted upon opposite sides of the support, power means for moving the leaves angularly toward a matrix positioned upon the support, each of the leaves having an abutment for supporting an insole blank, means for adjusting the matrix longitudinally and heightwise of the abutments on the leaves, and resilient means carried by the leaves for pressing the blanks against the matrix.

10. An insole spotting machine comprising a frame, a matrix support carried by the frame, leaves pivotally mounted upon opposite sides of the support, means for moving the leaves angularly toward a matrix positioned upon the support, means on the leaves for supporting insole blanks, means adjacent to the supporting means

for retaining the blanks on the supporting means during initial movement of the leaves toward the matrix, and means for retracting the retaining means upon approach of the leaves to the matrix.

11. An insole blank spotting machine comprising a frame, matrix supports carried by the frame, leaves pivotally mounted on the frame, leaves pivotally mounted on the frame upon opposite sides of the matrix supports, insole blank supporting means carried by the leaves, abutments on the leaves for positioning blanks along the supporting means, means mounting the matrix supports for adjustment heightwise of the blank supporting means, a stop on the frame for locating a matrix longitudinally of the supports in predetermined relation to the abutments, and power-operated means for closing the leaves.

5 10 15

12. An insole spotting machine comprising a frame, a matrix support carried by the frame, means for adjusting the position of the matrix longitudinally and heightwise of the frame, leaves pivotally mounted upon opposite sides of the support, means for moving the leaves angularly toward a matrix positioned upon the support, means on the leaves for supporting insole blanks, means adjacent to the supporting means for retaining the blanks on the supporting means during initial movement of the leaves toward the matrix, and means for retracting the retaining means upon approach of the leaves to the matrix.
